ENVELOPE OPENER

Filed Sept. 17, 1927

UNITED STATES PATENT OFFICE

RICHARD GLASSER, OF SAN FRANCISCO, CALIFORNIA

ENVELOPE OPENER

Application filed September 17, 1927. Serial No. 220,219.

The present invention relates to improvements in an envelope opener, and has particular reference to that class of openers in which, through the co-operation of two blades, an extreme edge of an envelope is cut away and separated from the body thereof so as to cause the envelope to be opened along an entire edge. The present invention more particularly constitutes an improvement on my envelope opener described and claimed in my United States Patent, No. 1,517,625, of December 2, 1924.

In my invention two blades arranged in transverse planes co-operate in cutting the edge of the envelope, and while in the former patent protection was secured on the means for imparting movement to one of the blades, it is proposed in the present invention to provide means for moving the second blade for better co-operation with the first blade in securing cutting action. It is further proposed in the present invention to provide certain improvements in the arrangement of the second blade which allow the latter to be adjusted with a high degree of accuracy, and to be operated to better advantage. Further objects and advantages of my invention will appear as the specification proceeds.

The preferred form of my invention is illustrated in the accompanying drawing, in which

Figure 1 shows a front view of my envelope opener with the front wall partly broken away;

Figure 2, a vertical section taken along line 2-2 of Figure 1;

Figure 3, a horizontal section taken along line 3-3 of Figure 1;

Figure 4, a perspective detail view of one cutting blade;

Figure 5, a perspective detail view of the co-operating cutting blade;

Figure 6, a sectional detail view taken along line 6-6 of Figure 1; and Fig. 7, a section along line 7-7 of Fig. 2.

While I have shown only the preferred form of the invention, I wish to have it understood that various changes or modifications may be made within the scope of the claims

hereto attached without departing from the spirit of the invention.

In its preferred form, my invention comprises a housing 1 presenting a rear wall 2, a stepped front wall 3, a top 4, and stepped sides 6, giving to the housing the general form shown in the drawing. Along each side of the housing are arranged two guide bars 7 and 8 forming a vertical guideway for the blade 9 shown in detail in Figure 4, which latter may be reciprocated by mechanism described in the above mentioned patent, and including a handle 11 pivoted in the sides of the housing at 12 and operating through a pin 13 on a slide 14 on the stem 16, which latter slide becomes operative through links 17 on a second set of links 18 operatively connected through members 19 to two projections 21 rising from the blade 9, so that depression of the handle 11 causes the blade to move downwardly over the resistance of a spring 22, which latter on release of the handle moves the blade upward to its original position. No claim is made for this construction in the present application. Along the left side of the housing as viewed in Figure 1, and shown particularly well in Figure 2, there is provided a block or ledge 23, fixed relative to the housing and formed with an upwardly projecting lug 24 spaced from the blade 9 by a considerable distance. On the flat surface 26 of this ledge, between the lug 24 and the blade 9, there is provided a sliding block 27 presenting toward the blade two spaced prongs 28, between which is hinged one end 31 of the second blade 32 shown in detail in Figure 5, a suitable ball bearing 33 being preferably provided underneath the hinge of the blade. The sliding block 27 is arranged in such a manner that the inner edge of the blade 32 just clears the descending blade 9. The amount of clearance may be adjusted to a nicety by means of a screw 34 threaded through the lug 24 and extending into a recess in the block 27 in which it is held against endwise motion by a set screw 36 riding in a groove 37 in the screw 34. It will be seen that turning of the screw 34 moves the sliding block 27 in one direction or the other, according to the direction of rotation. To hold the 100

sliding block 27 in its adjusted position I provide a second screw 38 extending through a slot 39 in the side wall into the slide, and drawing the latter toward the side walls.

- 5 5. A cover plate 41 overlies the front portion of the housing formed by the stepped side walls and has angle iron 42 secured to the underface thereof, which latter forms an abutment for two springs 43 bearing on the free 10 end of the blade 32 for normally pushing the free end of the blade into the path of the vertical blade, 9, the advance of the horizontal blade 32 being stopped by a guide 44 provided on the opposite side of the vertical 15 blade 9. The springs 43 are guided by suitable pins 46 extending from the face of the horizontal blade 32. The extreme free end of the horizontal blade 32 rides on a ledge 47 provided along the opposite side 6, roller 20 bearings 48 being interposed between the ledge and the blade, and being accommodated in a pocket 49 formed at the end of the blade as shown in Figure 5.

The housing is mounted on a suitable base 25 51 preferably formed with a longitudinal slot 52 extending under the operating area of the two knives so as to allow the separated edges of the envelopes to be discharged therethrough. When not in use, this slot may be 30 covered up by means of a removable plate 53.

The operation of my device will be readily understood from the foregoing description. The envelope to be opened is placed on the 35 cover plate 41 so that its front edge lies up against the guide 44 on the far side of the vertical blade. While the machine is at rest the cutting edge of the vertical blade lies over the front edge of the envelope as indicated 40 in Figure 2, and the horizontal blade naturally assumes a position with its hinged end just clearing the vertical knife, and its free end projecting into the path of the vertical knife and urged toward the guide 44. If now 45 the handle 11 is depressed, the vertical knife descends and while doing so forces the horizontal blade out of its way while co-operating with the same for cutting the envelope. The result of the operation is the removal of an 50 extremely narrow edge portion of the envelope, and a perfectly clear cut.

It will be noted that where the blade 9 is reciprocated in the manner shown in the drawing, the cutting edge should be made 55 inclined. If the vertical blade is operated in a different manner, as for instance with one end hinged, a straight cutting edge would co-operate with the horizontal blade in a similar manner.

60 I claim:

1. In an envelope opener of the character described, a blade hinged at one end only, roller bearings supporting the hinged end, anti-friction bearings supporting the free end 65 of the blade, yielding means operative on the

blade and a second blade coacting with the first blade for producing cutting action and causing the first blade to retreat during the cutting action.

2. In an envelope opener of the character described, a frame structure having a blade movable therein and a member movable transversely to the plane of the blade, a second blade hinged in said member for co-operation with the first blade, means for adjusting the position of said member and means for locking the same in adjusted position. 70

3. In an envelope opener of the character described, a frame structure having a blade movable therein and a block movable transversely to the plane of the blade having two prongs pointing toward the blade, a second blade hinged between said prongs for co-operation with the first blade, and means for adjusting the position of the block relative to the first blade. 75

4. In an envelope opener of the character described, a frame structure having a blade movable therein and a guide along one face of the blade, a second blade hinged at one end for movement in a transverse plane for co-operation with the first blade in producing cutting action and yielding means urging the free end of the second blade toward the guide in combination with means for adjusting the position of the hinged end of the blade. 80
